UNITED STATES PATENT OFFICE.

LOUIS J. CRECELIUS, OF ST. LOUIS, MISSOURI, ASSIGNOR TO ANDREW WARREN, OF SAME PLACE.

LIFTING-JACK.

SPECIFICATION forming part of Letters Patent No. 430,421, dated June 17, 1890.

Application filed April 14, 1890. Serial No. 347,848. (No model.)

To all whom it may concern:

Be it known that I, LOUIS J. CRECELIUS, of St. Louis, in the State of Missouri, have invented a new and useful Improvement in 5 Lifting-Jacks; and I do hereby declare that the following is a full, clear, and exact description of the same.

My invention relates to lifting-jacks, and is designed as an improvement upon the form 10 of jack shown in Patent No. 410,074, dated August 27, 1889, in which patent is shown a lifting-bar with a lifting and holding grip, the said grip consisting of a clutch-box carrying a wedge or like gripping device with a 15 loop operated upon by a handle or lever, the said loop being pivoted to the clutch-box and adapted to bear upon and apply pressure to the wedge or like device.

In the present invention is included the 20 lifting-bar of Patent No. 383,710, dated May 29, 1888, which is provided with a tapering face or groove, or, if desired, the lifting-bar may have parallel sides, a clutch-box carrying the lifting-grip, and a second clutch-box 25 carrying the holding-grip, with means for operating both grips, the one to lift the bar and the other to release the same. The improvements in the present case relate particularly to the clutch-boxes and grips carried thereby, 30 as will be hereinafter particularly set forth and specifically claimed.

In the accompanying drawings, Figure 1 is a side elevation of a jack embodying my improvement with a part of the standard broken 35 away to show the lower clutch-box. Fig. 2 is a front elevation of the standard with the lifting-bar partly shown and the clutch-box of the holding-grip shown in dotted lines. Fig. 3 is a section on line $x-x$ of Fig. 1. Fig. 4 is a detail plan view of the gripping-loop. Fig. 5 is a section on line $z-z$ of Fig. 1. Fig. 6 is a plan view of the handle-socket. Fig. 7 is a section on line $y-y$, Fig. 1.

The standard shown at A is of any ordinary or improved construction, while, as I have said, the lifting-bar B may be tapering or be provided with the usual cap a, having a serrated upper face and lifting-foot b at its lower end. The clutch-box carrying the lifting-grip is shown at C, this box being of approximately U shape in side elevation, rect-

angular openings being formed in the upper and lower limbs c' of the U, through which passes the lifting-bar, as shown in Fig. 5. The bottom of the clutch-box C rests normally on 55 the upper end of the standard, as shown in Fig. 1. The clutch-box carries a grip which has a central cylindrical portion c, with arms d, extending at right angles to the part c and passing outside the line of the clutch-box. These 60 arms d are curved, and their ends are adapted to engage the ends of the lever D, as at e, this lever having journals f, which have bearings in the offset g of the standard, as in Figs. 1 and 2. The curvature of the part c corresponds to the curvature of the clutch-box, which it neatly fits, as shown in Fig. 1; but in the front side of the part c it is notched, as shown at h, this notched portion being of equal width but greater depth than the channel in the lifting-bar, if the bar is formed with a channel. This notch provides a straight gripping-face. A clutch-block i is interposed between the gripping-loop and lifting-bar, as shown in Figs. 1 and 5, and thus when a downward pressure is applied to the lever D the 70 grip is turned in its bearings, acting as an eccentric or cam, forcing the clutch-block against the face of the lifting-bar. As the handle is raised the arms d fall by gravity 75 until the inner wall of the notch h is in a line parallel to the face of the clutch-block, and in this position there is no gripping action.

The clutch-box for the holding-grip is shown at E. The clutch-block is shown at i' and the 80 gripping-loop at c'. The releasing-lever is shown at k in Fig. 1. This holding clutch-box is movable vertically within a chamber E' in the standard, and the arms d' of the holding-loop c' are arranged to bear upon the 85 bottom of this chamber, and the block i' is interposed between the loop and the lifting-bar. It will be seen that when the lifting-bar is raised by the action of the lifting-lever and clutch-box C its downward tendency under the weight will cause the holding clutch-box to move downwardly, and as the arms d' bear upon the bottom of the chamber E' the arms will be moved and the loop turned, causing the central cam part c' to force the block 90 against the lifting-bar, thus holding the same. In order to release the holding-grip to allow 95 100

the lifting-bar to fall, a releasing-lever *k* is provided, the arms *k'* of which are arranged to bear upon the under side of the clutch-box, and when the outer end of the lever is depressed the clutch-box will be raised and the lifting-bar released by the downward turning of the loop *c'* and the consequent loosening of the block *i'*.

It will be observed that both clutch-boxes have open sides and the gripping-loops are adapted to be seated by slipping them between the upper and lower branches *c*⁴ of the U-shaped boxes. They, together with the blocks *i* and *i'*, are easily removable when the lifting-bar is removed. The clutch-boxes are also removable and all these parts are locked in position by the insertion of the lifting-bar. This is also true of the lifting-lever, the journals *f* of which are inserted in the bearings *g*, which are open at one end. The bearing parts *c* *c'* of the grips journal against the internally-rounded wall *c*² of the clutch-boxes throughout the entire width thereof, and thus a strong construction is provided.

25 I claim as my invention—

1. In combination, the standard A, the lifting-bar B, a lifting-lever D, a clutch-box substantially U-shaped in side elevation having upper and lower limbs *c*⁴, perforated for receiving the lifting-bar, and a grip carried by said clutch-box, substantially as described.

2. In combination, the standard, the lifting-bar, a lifting-lever, a clutch-box having a wall *c*², with its interior rounded, and a turning grip carried by said box and seated against the said wall throughout the width thereof, substantially as described.

3. In combination, the standard, the lifting-bar, a lifting-lever, a clutch-box, a grip having a bearing and gripping part seated therein, and the arms *d*, extending outside in position to be operated, the said lifting-lever bearing under the ends of the arms *d*.

4. In combination, the standard, the lifting-bar, the lifting-lever, the clutch-box, and grip, the said lever being removably journaled and retained in place by the lifting-bar, substantially as described.

5. In combination, the standard, the lifting-bar, the lifting-lever and clutch-box, and a vertically-removable holding clutch-box with a releasing-lever acting directly upon said clutch-box, substantially as described.

6. In combination, the standard having a chamber E', the lifting-bar, the lifting-lever, the lifting-clutch box, the vertically-movable holding-clutch box within the chamber E', the grip having arms *d'* to bear upon the bottom of the chamber, and the releasing-lever to operate the clutch-box vertically, substantially as described.

7. In combination, a standard, a lifting-lever, a clutch-box, a lifting-bar having a channel, a grip having a cylindrical part *c* to bear upon the face of the bar, and a notch *h* and a clutch-block in said notch bearing within the channel of the bar, substantially as described.

In testimony whereof I have signed my name to this specification in the presence of two subscribing witnesses.

LOUIS J. CRECELIUS.
